UNITED STATES PATENT OFFICE.

GRACE ELIZABETH McNAMARA, OF PLYMOUTH, INDIANA.

CORSET CLASPS.

1,416,850.

Specification of Letters Patent. Patented May 23, 1922.

Application filed December 31, 1920. Serial No. 434,275.

To all whom it may concern:

Be it known that I, GRACE E. McNAMARA, a citizen of the United States, and a resident of Plymouth, in the county of Marshall and

5 State of Indiana, have invented a new and useful Improvement in Corset Clasps, of which the following is a full, clear, and exact description.

My invention relates to improvements in 10 corset clasps, and it consists in the combinations, constructions and arrangements herein described and claimed.

The ordinary corset clasp is objectionable in several particulars. The main objection 15 is that fastening members usually project to some extent, so that in many instances they rub and chafe the flesh, thus causing sores which may develop into serious maladies. The projection of the fastening devices is also liable to cause the pinching of 20 the flesh when the corset is fastened, especially when worn by stout persons.

The fastening members of the ordinary corset which are liable to pinch or chafe the 25 flesh are those on the inside of the corset, but the fastening members on the outside of the corset are also objectionable, since many times the clothing is torn by these projecting fastening members.

30 An object of my invention is to provide a corset clasp in which the fastening members are covered by the body portion of the corset, in which there are no inside or outside projecting members, thus obviating the 35 chafing or pinching on the inside of the corset, or the liability of tearing or wearing the clothing on the outside.

A further object of my invention is to provide a fastening device of the type described 40 which will permit the corset to be clasped and unclasped readily.

Other objects and advantages will appear in the following specification, and the novel features of the invention will be particularly 45 pointed out in the appended claim.

My invention is illustrated in the accompanying drawings, forming part of this application, in which—

Figure 1 is a front view of the corset provided with my clasping means,

Figure 2 is an enlarged section along the line 2—2 of Figure 1,

Figure 3 is a section along the line 3—3 of Figure 2,

55 Figure 4 is a front detail view showing the male members of the clasping means,

Figure 5 is a front detail view showing the female members of the clasping means,

Figure 6 is a section along the line 6—6 of Figure 4, and

Figure 7 is a section along the line 7—7 of Figure 5.

In carrying out my invention, I make use of any ordinary form of corset, such as that shown at 8 in Figure 1. The edges of the 65 corset overlap and are provided with steels, such as those shown at 9 and 10, which are sewed or otherwise secured to the body portion. One of these steels is bent back upon itself, as shown at 11, and side flanges 12 70 are turned inwardly between the bent over portion and the steel strip, so that they lie close to the steel strip, thus providing the female clasping member. The male clasping member consists of a tongue 13 which is bent 75 over and is slightly tapered, as shown in Figure 5.

It is of course desirable to apply these clasping members wherever they are needed. In the drawing I have shown an upper 80 member at 14, two intermediate members at 15, and two lower members at 16, but it will be understood that more or less might be used as desired. In order to manipulate the corset, I provide an extending flap 17 on the 85 outside edge, by means of which the body portion of the corset may be grasped to aid in unclasping or clasping the corset.

In the drawings the corset clasping members are shown in relative positions which 90 are exaggerated for the sake of clearness. As a matter of fact, these clasping members are close to the steels upon which they are carried, so that the corset portions may lie closely to each other, instead of being spaced 95 apart, for instance, as shown in Figures 2 and 3. The clasping members are made relatively thin, so that a corset may fit snugly without bunching along the fastening line. They are, however, of sufficient strength to 100 obviate any danger of bending or breaking.

A corset provided with my improved clasping devices has a substantially smooth interior along the line where the two parts are connected by the clasping devices. This 105 does away with any danger of chafing or rubbing of the flesh by the clasping devices, since of course they are between the two adjacent corset parts. It also obviates any danger of tearing the clothing, since there 110 are no outside projections upon which the clothing may catch. The device is simple in

construction, easily applied to the ordinary form of corset.

I claim:

The combination with a corset having overlapping portions, of a metal strip secured to the inner face of the outer overlapping portion, and a metal strip secured to the outer face of the inner overlapping portion, one of said strips having a plurality of integral portions bent back upon the strip, each of said bent back portions having flanges bent inwardly to lie between the bent

back portions and the body portion of the strip, and to constitute female clasp members, the other strip having integral portions 15 bent back upon the strip to constitute male clasp members and arranged to engage the corresponding female clasp members, said clasp members lying between said strips when in clasping engagement, one of said 20 overlapping corset portions having an extension flap for facilitating the clasping and unclasping of the corset.

GRACE ELIZABETH McNAMARA.
